UNITED STATES PATENT OFFICE

ANTHONY D. ZIMMER, OF RUSSELL, NORTH DAKOTA.

GAGE OR MARKER AND RULE.

No. 822,094.

Specification of Letters Patent.

Patented May 29, 1906.

Application filed October 4, 1905. Serial No. 281,345.

To all whom it may concern:

Be it known that I, ANTHONY D. ZIMMER, a citizen of the United States, residing at Russell, in the county of Bottineau and State of North Dakota, have invented certain new and useful Improvements in Gages or Markers and Rules, of which the following is a specification.

The object of my invention is to provide a useful and simple gage or marker and rule which will be especially adaptable for use by carpenters or joiners in putting on base-boards of rooms.

For a full description of the invention and the merits thereof and also to acquire a knowledge of the details of construction of the means for effecting the result reference is to be had to the following description and accompanying drawings, in which—

20 Figure 1 is a side elevation of the device. Fig. 2 is a side view of one of the members designed to form a rule. Fig. 3 is a view illustrating the application of the device.

Corresponding and like parts are referred to in the following description and indicated in all the views of the drawings by the same reference characters.

My improved base-board marker or gage comprises two members 1, preferably of wood or similar material, incased at one end or embraced between brass or other metallic plates 2, hinged together by a knuckle-joint 3. The members 1 are provided at their pivotally-connected ends with angular extensions 4, having right-angle faces 4^a and 4^b, as illustrated in Fig. 1. When the members 1 are moved toward each other into the position shown in Fig. 1, the faces or edges 4^b of the angular extensions 4 abut against each other, and as such faces extend parallel with the side edges of the members 1 the latter are maintained in true parallel relation to each other. When in this relation, it will be seen also that the other edges or faces 4^a of the extensions 4 form a continuous edge at right angles to the side edges of the members 1.

Each of the members 1 is provided along one face with graduations in inches and feet, as shown at 5, so that the device when the two members are in open position or longitudinal alignment with each other may be used as a straight-edge or rule. The other ends of the members 1 are preferably tipped by brass or other metal caps 6.

In the practical application of my improved device, which is intended for use primarily to assist carpenters in accurately joining base-boards to the base-blocks, the device is used as shown best in Fig. 3. The base-block having been secured in place 55 against the wall-casing B, the base-board C is moved in contiguous relation to the base-block A, and my improved gage or marker is then inserted downwardly and inside of the base-board C with one member 1 flat against 60 the side edge of the base-block A. When in this position, it is evident that the base-board C may be marked by a pencil or the like accurately along the face of the member 1 of the gage, so as to readily indicate the proper 65 line upon which to subsequently cut the base-board so that it will accurately fit into its proper place along the side of the base-block A.

Having thus described the invention, what is claimed as new is—

75 A gage or marker for use in fitting base-boards to the base-block of a room, comprising two members 1 pivotally connected together at one end and provided at their pivoted ends with inwardly-extending exten- 80 sions 4 provided with right-angled faces or edges, two of said faces being designed to abut against each other to hold said members in parallel relation, so that the device may be conveniently straddled upon the base-board 85 and the latter marked at the proper point.

In testimony whereof I affix my signature in presence of two witnesses.

ANTHONY D. ZIMMER. [I. S.]
